UNITED STATES PATENT OFFICE.

GUSTAV TÜRK, OF MEININGEN, GERMANY, ASSIGNOR, BY MESNE ASSIGNMENTS, TO THE CHEMICAL FOUNDATION, INC., A CORPORATION OF DELAWARE.

MACHINE FOR PRODUCING SMALL STRIPS OF FIBROUS MATERIAL.

1,395,751.

Specification of Letters Patent.

Patented Nov. 1, 1921.

Application filed May 5, 1919. Serial No. 294,994.

To all whom it may concern:

Be it known that I, GUSTAV TÜRK, subject of Germany, residing at Meiningen, Rohrstrasse 16, Germany, have invented certain 5 new and useful Improvements in a Machine for Producing Small Strips of Fibrous Material, of which the following is a specification.

In manufacturing paper, difficulties have 10 frequently arisen, when narrow strips of paper were to be produced, the width of which being predetermined directly when being formed from the paper pulp. These difficulties are particularly present, when 15 the paper pulp contains long fibers or crisp material. The attempt has been made, heretofore, to form the strips on the sieve cloth of the paper machine, by providing the sieve cloth with impermeable strips or 20 ledges to prevent the paper pulp from adhering to the sieve at such places. In cylinder paper machines such division can be carried out without difficulty, however, in web paper machines the difficulties are so 25 great that it appears impracticable to provide the metal sieve cloth with such strips. Though these difficulties are not present with cylinder paper machines, yet with these it is only possible to cause the material 30 to adhere to the sieve surface, when specially prepared for this purpose.

In any case, particularly when the impervious strips are fastened to the sieve in a defective manner, it will be impossible to 35 produce paper—or other fibrous strips having smooth and even edges. The edges of the strips have rather a tendency to combine with the neighboring strips, particularly, when it is desired to utilize the full breadth 40 of the machine as much as possible and for this reason the impervious parts are made comparatively narrow.

It has further been attempted to divide 45 the paper strips from one another by directing small streams of water against the sieve, however, these trials have not proved to be successful.

According to the present invention the 50 above mentioned difficulties are avoided by the aid of a number of thin disks or rings, which are placed on edge on the metal sieve, thus forming a sort of trough, in which the sieve forms the bottom which is thereby divided into separate strips. The paper pulp 55 can only settle in the intermediate spaces on

the sieve between the disks, as it is continuously moving forward. The paper sieve leaves the said disks furnished with the fiber strips, which have very even and smooth edges.

Figure 1 shows diagrammatically a sectional elevation of a machine constructed according to the present invention, and Fig. 2 is a longitudinal section of this machine.

In the construction shown the disks or rings *a*, which rest on the sieve cloth *b* border the pulp strips *c*, and correspond in number to the number of strips to be produced. They are held together by long bolts *d* and are held apart by distance pieces *f*, the thickness of which corresponds to the width of the strips to be produced.

The cylinder, which is formed by the disks being bolted together is provided with end walls *g*, which determine the breadth of the 75 complete group of strips. The composite cylinder requires no special driving shaft, because it rests on rolls of the metal sieve *b* and is rotated by the forward movement of the sieve.

Within the metal sieve an impermeable endless cloth is arranged, which can be made of any impervious material, such as leather, parchment-paper, oil-cloth and so on and which prevents the escapement of the liquid. 85 The endless cloth *s* runs over the guiding rolls *h* about the breast roll *i* and about an adjustable guiding roll *k*. By adjusting the roll *k*, the cloth *s* can be shortened or lengthened to change the length *y* that is to say the 90 time during which the sieve after leaving the leather cloth *s* travels within the liquid, whereby the thickness of the paper strips produced is determined.

The pulp is fed between the disks preferably by a shoot *m*, which is open on one side. The manner, in which the pulp is fed depends on the shape of the disks *a*. The pulp fed settles between the disks *a* on the metal sieve *b*, which moves in the direction 100 shown by the arrow, when passing the length *y*. On the way *x*, between the edge of the liquid and the line, in which the disks *a* rest against the couch-roll *n*, the newly 105 formed strips are partly deprived of their water, by which the adhesion on the metal sieve is favored. In passing over the couch-roll, which, as is usual in paper machines, is adapted to suck off moisture, the strips are deprived of their water content to a greater de- 110

gree. Finally the strips *c* after passing the couch-roll *n* are led away by any suitable means.

I claim:

- 5 1. Machine for manufacturing narrow strips of fiber from paper pulp and the like, comprising an endless traveling sieve, an impermeable apron within the sieve and in contact with the sieve for part of its length, a 10 plurality of disks, resting on the sieve and means for feeding pulp between the disks.
- 15 2. Machine for manufacturing narrow strips of fiber from paper pulp and the like, comprising an endless traveling sieve, an impermeable apron, a plurality of disks resting 20 on the sieve, said impermeable apron being in contact with the sieve for a section of that part on which the disks rest, and means for feeding pulp between the disks.
- 25 3. Machine for manufacturing narrow strips of fiber from paper pulp and the like, comprising an endless traveling sieve, an impermeable apron within the sieve and in contact with the sieve for part of its length, a plurality of disks resting on the sieve to 30 form troughs, and means for feeding pulp between the disks.
- 35 4. A machine for manufacturing narrow strips of paper from paper pulp and the like,

comprising the combination of an endless 30 permeable conveyer, an impermeable apron in contact with said conveyer for part of its travel, a plurality of disks resting on said conveyer, and means for feeding pulp between said disks.

35 5. A machine for manufacturing narrow strips of paper from paper pulp and the like, comprising permeable conveying means, means for preventing the escape of liquid through said conveying means and in contact with said conveying means for part of its travel, means for determining the width of the paper strips, said means resting upon said conveying means, and means for feeding pulp between said determining means.

40 6. A machine for manufacturing narrow strips of paper from paper pulp and the like, comprising an endless permeable conveyer, an impermeable apron in contact with said conveyer for a part of its travel, means for determining the width of the fiber strips, 45 said means resting upon said permeable conveying means, and means for feeding pulp between said determining means.

50 GUSTAV TÜRK.
